UNITED STATES PATENT OFFICE.

HAROLD HASTINGS RAYNOR, OF NEW YORK, N. Y., ASSIGNOR TO THE PALMOLIVE CO.,
OF MILWAUKEE, WISCONSIN, A CORPORATION OF WISCONSIN.

DESIGN FOR A CONTAINER.

60,370.

Specification for Design. Patented Feb. 7, 1922.

Application filed May 6, 1921. Serial No. 467,288. Term of patent 7 years.

To all whom it may concern:

Be it known that I, HAROLD HASTINGS RAYNOR, a citizen of the United States, residing at New York, in the county of Queens and State of New York, have invented a new, original, and ornamental Design for Containers, of which the following is a description, reference being had to the accompanying drawing, forming part thereof.

The figure is a perspective view of my new design.

I claim:

The ornamental design for a container, as shown.

HAROLD HASTINGS RAYNOR.

In presence of—

K. E. WALSH.
